INVENTOR

Bernhardt W. Bloomquist

John W. Maupin.

ATTORNEY

UNITED STATES PATENT OFFICE.

BERNHARDT W. BLOOMQUIST, OF SEATTLE, WASHINGTON.

VERTICAL-CONTROL DEVICE FOR AIRPLANES.

Application filed September 25, 1922. Serial No. 590,338.

To all whom it may concern:

Be it known that I, BERNHARDT W. BLOOMQUIST, a citizen of no country, and a native of Finland, having legally declared 5 my intentions of becoming a citizen of the United States, and residing at Seattle, in the county of King and State of Washington, have invented a new and useful Vertical- 10 Control Device for Airplanes, of which the following is a specification.

This invention relates to vertical control devices for airplanes and the principal object of the invention is to provide a vertical control comprising propellers arranged to 15 lift the airplane vertically from the ground. Another object is to provide automatic means whereby the slant of the blades may be regulated to increase or decrease the lifting power of said propellers at all times. A 20 further object is to provide a relatively large overhead wing surface symmetrically disposed above the center of gravity of the machine body and adapted to serve as a parachute while descending. 25 With the above and other objects in view which will appear as the description proceeds, the invention consists of the novel construction, adaptation, arrangement and combination of parts hereinafter described 30 and claimed.

These objects are accomplished by devices illustrated in the accompanying drawings wherein—

Figure 1 is a top plan view of the device; 35 Fig. 2 is a view in side elevation with certain parts broken away;

Fig. 3 is a view in transverse vertical section taken substantially on a broken line 3, 3 of Fig. 1; and

Fig. 4 is a fragmentary top plan view of the reciprocating track members and associated parts.

Referring to the drawings, throughout which like reference numerals designate like 45 parts, the numeral 5 designates the body of an airplane having a propeller 6 driven by an engine partly shown at 7 for going ahead. The numeral 8 designates the overhead wing which is secured to said body by stay rods 9, 50 while the numeral 10 indicates the rudder and the numeral 11 indicates a deck or flooring.

An engine 12, shown in outline, is centrally mounted on the flooring 11 and a horizontal propeller shaft 13 extending forward 55 and aft from said engine is mounted in bear-

ings 14 and 15 adjacent the outer end portions thereof. Bevel gear wheels 16 and 17, secured to the outer ends of said shaft, mesh with smaller gears 18 and 19 secured to vertical shafts 20 and 21.

The vertical shafts 20 and 21 are secured at their lower ends in ball bearings 22 and 23 fastened to the flooring 11. Transverse members 24 and 25, secured across the top 65 of the body 5, serve as bearings for said vertical shafts and ball bearings 26 and 27, bearing upwardly thereagainst, support the weight of said body.

Hubs 28 and 29 are fixedly secured to the upper ends of the shafts 20 and 21 and spokes 30 and 31 have their inner ends secured thereto in spaced apart radial relation and their outer ends are similarly secured to rims 32 and 33. Anti-friction devices 34 and 35 are secured to the wing 8 with their rollers arranged to bear against said rims and the stay rods 9 are secured to rings on the undersides of said devices. Propeller blades 36 and 37 are secured to said spokes in such 80 manner that they may turn transversely thereon and prevented from longitudinal movement by any suitable means, not shown. The inner ends of said blades terminate short of said hubs and are beveled as clearly shown 85 in Fig. 1 of the drawings, and rollers 38 and 39 are operatively secured to the underside corners thereof for reasons presently set forth.

Standards are provided in transverse 90 alignment with the shafts 20 and 21 comprising uprights 40 and 41 joined together by straps 42 extending around the underside of the body 5. Said standards converge upwardly and are bifurcated at their upper 95 end portions to form arms 43 and 44. Said arms are curved inwardly and their end portions are further bifurcated to form pairs of upright fingers 45 and 46. Webs 47 join said arms to central ball bearings 48 through 100 which said vertical shafts pass thus serving to retain same in upright alignment.

Each pair of fingers 45 and 46 serves as supporting bearings for outer track members 49 and also for inner track members 50 105 telescopically mounted therein. Said outer track members are provided with diametrically opposite depending rods 51, while said inner track members are provided with corresponding rods 52. Said rods are disposed 110 in transverse alignment with the shafts 20 and 21 and upright standard members 40

and 41. The lower ends of said rods are pivotally secured to levers 53 and 54 extending through and pivotally secured within apertures provided in said upright stand 5 and members as clearly shown in Fig. 3.

The rollers 38 are arranged to engage the outer track members 49 while the rollers 39 engage the inner track members 50 and it will be obvious that by operating the levers 10 53 and 54 simultaneously vertical reciprocal motion will be communicated through said track members to said rollers and will cause the propeller blades 36 and 37 to assume any pitch which may be desired in causing 15 the machine to climb vertically from the ground.

It will be understood that the machine is constructed of light material and a powerful engine is used for driving the overhead 20 propellers. The body portion is to be relatively small compared with the wing surface, ball bearing and roller devices are employed to reduce friction to a minimum, and the gears are designed to greatly accelerate 25 the speed of the vertical shafts. As shown, a separate engine is employed to drive said vertical shafts carrying the overhead propellers, although same may be geared to a single engine both for going ahead and 30 climbing.

Although not shown in the drawings, it is intended in practice to connect both pairs of levers 53 and 54 to a single control rod in any suitable manner and so arranged that 35 the pilot or engineer may manually regulate the pitch of the overhead propeller blades, by hand or by foot, from a central or other convenient position.

While the foregoing description taken in 40 connection with the accompanying drawings is intended merely for illustration, it will be obvious, when the device is built in the

proper proportions, that the machine will lift itself vertically from the ground, and, in conjunction with the engine and propeller 45 for going ahead, may be maneuvered at will. In fact the perfect control of the pitch of the propeller blades will enable the machine to stand still in the air, while the parachute arrangement of the overhead wing surface 50 will enable same to descend vertically to the ground.

Having thus described my device, it being understood that such changes may be resorted to as are within the scope and spirit 55 of the invention, what I claim and desire to secure by Letters Patent is:—

In combination with the body of an airplane of a vertical control device comprising a relatively large wing surface symmetrically secured above said body, a horizontal shaft mounted within said body, driving means for said shaft, vertical shafts geared to said horizontal shaft, anti-friction bearings for said shafts, hubs secured to the upper ends of said vertical shafts, spokes radially secured to said hubs in the plane of said wing surface, rims secured to the outer ends of said spokes within annular apertures in said wing surface, roller bearings for said 70 rims, propeller blades pivotally mounted on said spokes, said blades having beveled inner ends terminating short of said hubs, standards having bifurcated arms and fingers, outer and inner annular track members telescopically mounted in said standards, rollers secured to the inner corners of said propeller blades adapted to engage said track members, and lever means adapted to impart reciprocal movement to said track members 80 to regulate the pitch of said propeller blades.

BERNHARDT W. BLOOMQUIST.
